UNITED STATES PATENT OFFICE.

FRIEDRICH LUTZMANN, OF ZURICH, SWITZERLAND, ASSIGNOR TO JOHN B. METZLER,
OF ZURICH, SWITZERLAND

MORTISE LOCK.

Application filed December 16, 1920. Serial No. 431,258.

To all whom it may concern:

Be it known that I, FRIEDRICH LUTZMANN, a citizen of the German Republic, residing at Zurich, Switzerland, Stampfenbachstrasse 5 No. 48, have invented new and useful Improvements in a Mortise Lock (for which I have filed application for patent in Germany, October 18, 1919), of which the following is a specification.

10 The present invention relates to a new and improved mortise lock having a bolt rotatably mounted within the lock-case adapted to be actuated against the action of a spring by knobs, handles or the like.

15 One object of the invention is to provide a lock of the kind described in which the bolt may be secured in its locking position either by a key-operated tumbler or by a hand actuated stop.

20 A further object consists in the provision of means to prevent the locking of the bolt by the key-actuated tumbler if and as long as the said bolt is locked by the hand set stop. The lock cannot be actuated by the

25 key say from the outside of a room if the bolt has been locked by the stop which can only be actuated from the inside of the room.

A still further object consists in the provision of a lock, which shall be simple, strong and durable in construction and adapted to be used for any either right or left hand door.

I attain the last named object by forming the operative parts of the lock from strong sheet metal placing the same one beside the other in the case, all being arranged in one plane in such a manner that the lock case is very thin and needs only a narrow mortise 40 in the wooden door style.

Other objects of the invention relate to the provision of minor parts cooperating with the elements above noted and to details of construction all of which will be more 45 clearly set forth in the following specification.

With the above objects in view the invention resides in the parts and combinations of parts hereinafter described, and particularly set forth in the claim appended hereto.

In order that my invention may be clearly understood I have illustrated the same in the accompanying drawings, wherein:

Fig. 1 is a side elevation of the lock a side plate of the lock case being removed, the 55 bolt being shown in locked position.

Fig. 2 is a section on line A—B of Fig. 1.

Fig. 3 shows the face plate of the lock.

Figs. 4 and 5 show the strike-plate of the lock cooperating with the bolt. 60

The lock shown in the drawing comprises a case 1 one part being stamped and pressed from sheet metal which part is covered by a plate (taken off in Figs. 1 and 2). In the walls of the case 1 a pin 2 is fixed on which the bolt 3 is rotatably mounted. Bolt 3 is provided with a head 4 projecting through an opening in the face plate 5 of the case 1 said head 4 being adapted to engage the strike 21 fixed to the door frame. Against the bolt 3 abuts one end of spring 6 the other end of which rests on an arm 7 of a hub 8 rotatably mounted in the side walls of the lock case. The hub 8 which is provided with a squared hole to receive the spindle on which the knobs (not shown in the drawing) are fixed, is provided with a tooth 9 which is in engagement with an arm 10 of bolt 3 in such a manner that on rotation of the hub 8 the bolt 3 is rotated. The spring 6 tends to keep the bolt 3 in the position shown in Fig. 1 in which the head 4 projects from the face plate 5. With the arm 10 cooperates a tooth 17 of a second hub 16 journaled in the side walls of the case 1 adapted to 70 receive a spindle with square cross-section on which a knob 25 is fixed. The hubs 8 and 16 corresponding in shape and in size are interchangeable. Between the boss 16 and the front wall of the case 1 there is a 75 blade spring 18 which is under tension and which tends to hold the boss either in the position shown in Fig. 1 in full lines or in that shown in Fig. 1 in dotted lines. In the position shown in Fig. 1 in full lines the tooth 17 acts as a stop for the arm 10 and makes it impossible to turn bolt 3 by the tooth 9. On a pin 12 a tumbler 11 is 80 rotatably mounted which can be moved by a key inserted through the keyhole 14 from the position shown in full lines in Fig. 1 to that shown in dotted lines and vice-versa against the action of a spring 13. The one free end of the tumbler 11 is adapted to be 85 brought in engagement with the bolt 3 and to serve as a locking element which abutting

105

on the rear wall 15 of the case 1 prevents the forcing back of the bolt 3. If the tumbler 11 is moved by the key into the position shown in Fig. 2 the bolt 3 may be withdrawn and the door opened. To lock the tumbler 11 in the position shown in full lines Fig. 1 the hub 16 is rotated in such a manner that the hook 19 passes over the free end 20 of the tumbler 11 (see Fig. 1). In this position the bolt 3 is dead-locked. It is now impossible to shift the tumbler 11 over the bolt 3 and if the hub 16 is only to be set from the inside of a room the lock cannot be opened by a key inserted from the outside nor can the bolt be locked by the key. Only the person inside the room can unlock the door and the proprietor of a proper key cannot use it.

The head 4 of the bolt 3 is provided with a rib 20 bevelled on both sides in such a manner that the lock may be used for left hand doors as well as for right hand doors. The strike plate 21 is of angular cross-section and is provided with two cross slots 22, 23 to receive the rib 20 one slot being used for left hand doors and the other for right hand doors.

All the moving elements of the lock are

arranged in the same plane. They do not overlap and therefor the thickness of the lock is reduced to a minimum. The mortise to be made in the door style is narrow. When the hub 8 is worn it may be replaced by the hub 16.

The new lock as a whole is of very simple construction, is readily applied, and operates in a very satisfactory manner to accomplish the end for which it is designed.

Various changes may be made without departing from the spirit of my invention as claimed.

What I wish to secure by U. S. Letters Patent is:

A lock comprising in combination a case, a bolt rotatably mounted in said case, a hub connected with handles adapted to rotate said bolt, a hand operated element rotatably mounted in the case and adapted to lock the bolt, and a key operated tumbler, rotatably mounted in said case and adapted to be positioned behind the bolt in its locking position and having a projection adapted to be engaged by a hook on the latch-hub for the purpose set forth.

In witness whereof I affix my signature. 55
FRIEDRICH LUTZMANN.
